FIG. 2.

FIG. 1.

UNITED STATES PATENT OFFICE

2,514,889

AUTOMATIC CODE SELECTOR

William Walter McGoffin, New York, N. Y., assignor of one-fifth to S. S. Baker, New York, N. Y.

Application March 28, 1947, Serial No. 737,905

5 Claims. (Cl. 177—353)

1

This invention relates to an automatic selector of Morse code signals and more particularly to an apparatus designed to respond to a particular combination of such signals.

An object of this invention is to provide an apparatus which automatically responds to a predetermined series of dot and dash signals in such a way as to exclude any undesired combination and to perform this function in an accurate and simplified manner requiring a minimum of component parts. Thus, two relays perform four elements of timing, that is, dots, dashes, intervals and spaces, the time between the dots or dashes of a letter being designated as intervals and the time between letters being designated as spaces. The provision of the two timing relays in the manner hereinafter described permits the apparatus to operate over a wide variation of code speeds so that when the apparatus is set for a particular speed, it will respond correctly although receiving code signals which depart considerably from the predetermined speed setting.

Another object of this invention is to provide an automatic code responding apparatus which re-sets itself to starting position upon the reception of any undesired letter component, such a component comprising either a dot, dash, interval or space, and wherein the apparatus remains re-set until another letter is started. Thus, a part of a letter will not restore the apparatus to activity whereby false responses are avoided.

Another object of this invention is to provide an apparatus wherein two mechanically ganged stepper switches respectively respond to dots and dashes on the one hand, and intervals and spaces on the other hand, so that such signal components may be swiftly and accurately recorded thereby permitting faster and simplified operation as well as adaptability to varied code speeds.

Still another object of this invention is to provide neutral reception means whereby the letters of a signal will be accepted and a response produced whether or not the proper spacing between such letters is observed. This feature is of considerable importance in S O S signals where the letters are often run together without including letter spaces. Under such varying conditions of sending, the apparatus will nevertheless respond so as to sound an alarm when an S O S signal is received.

A further object of this invention, as represented by a modification, is to provide an apparatus of this type which in large measure automatically adapts itself to the code speed of reception. This is accomplished by the use of a

2

condenser element which sets the delay time of a relay so that the length of dashes, as opposed to dots, or, of spaces as opposed to intervals, can be measured. The condenser element is arranged to carry a charge which is influenced by the rate of code speed so that the delay time of the relay is correspondingly influenced and the signal characters are measured with the code speed as a factor.

10 This application is a continuation in part of my prior application Serial No. 560,862, filed October 28, 1944, now Patent Number 2,446,943.

Other objects of my invention will be apparent from the following description, it being understood that the above general statements of the objects of my invention are intended to describe and not limit it in any manner.

Fig. 1 is a schematic representation of the apparatus.

20 Fig. 2 is a schematic view illustrating a modified form of a delayed relay action.

The selector or stepper switch is of the dual type which, upon relay actuation, progressively wipes over a radially disposed series of contacts 25 arranged at two levels designated herein as switches S1 and S2. Switches S1 and S2 have their main or relay actuated arms ganged together for simultaneous movement. Each series of contacts are further selectively connected to one of a bank of switch positions, the selection depending upon the call which the apparatus is set up to respond. Thus, switch S1, upon which the dots and dashes are set up, includes a series of selector arms 25-29 etc. which may be set on any one switch position of the switch banks such as bank 15. The arms 25-29 etc. are normally set on the release or reset circuit 16 and when they are switched to one of the other circuits as hereinafter set forth, they select the dots and dashes of the desired combination.

30 Thus, if the first character of the predetermined call is a dot, the switch arm 25 is set at the first switch position of the bank 15. If a dash follows, the arm 26 is switched to the second switch position of bank 17.

40 During the operation of the apparatus, arm 31 of switch S1 successively wipes over the contacts 31-36 etc. each of which are selectively connected to the reset, dot or dash circuits according to the predetermined call.

50 The selector arms 100-105 etc. of the banks of switches of switch S2 are progressively set at either interval or space, the normal position of arms 100-105 being at the interval position as represented by interval wire 18. Thus, switch

3

series S2 is likewise provided with switch bank positions although each bank in series S2 has four positions as hereinafter set forth. The last space of the desired call is not set at "space" but the last used arm of the selector arms 100-105 etc. is set at "alarm" instead. It will be seen, therefore, that the call is set up by alternately proceeding from S1 to S2, setting up the dot and dash characters on S1 and the intervals and spaces at S2 where they occur in the call.

The dot and dash pulsations are applied through dash wire 68 or dot wire 69 to the dot and dash interpreter circuit 22 which is identified in Fig. 1 by broken lines. This enables each incoming pulsation to be checked as to its dot or dash character and the stepper switch is advanced or reset according to the correspondence of such character with the predetermined and pre-set call.

Pulsing relay 41 is connected to the output of an ordinary radio receiver which is tuned to the call frequency. Thus, pulsing relay 41 delivers the received signal to the apparatus for interpretation and alarm action if indicated. In the initial action, each incoming pulsation is applied to main switch arm 37 through wire 38 and contacts 39 and 40 of pulsing relay 41. If the incoming pulse coincides with the selector switch arm setting to the interpreter circuits, the arm 37 is allowed to advance through the action of the spring 42 which pulls the dog 43 against the action of the return spring 44 at the end of the pulsation. Stepper relay 45 is energized by the relay 41 through the contact 39 so that relay 45 receives the same potential that is applied to arm 37. This pulls armature 46 and drops the dog 43 into the next tooth. Then when relay 45 is released, dog 43 pulls the toothed wheel stepper 47 forward a notch through the action of spring 42. Stepper wheel 47 is maintained in its advanced position by pawl 48 which is controlled by reset relay 68. Mechanical armature 48a is operated by reset relay 68 and through the linkage shown simultaneously disengages the dog 43 and the pawl 48 allowing the spring 44 to return to the stepper wheel 47 to starting position.

Simultaneously with applying the pulsation to the relay 45, it is also applied to the dot and dash timing relay 50 through the contacts 65 and 66. Relay 50 is of the delayed closing type accomplished by the condenser 51 which is effectively interposed across the relay winding when it is not energized. The time delay includes the resistors 52-54 either one of which may be switched into the circuit so as to regulate the delay time of relay 50. In a practical embodiment, resistors 52-54 were 5000, 10,000 and 15,000 ohms respectively, while condenser 51 was 10 microfarads. The winding of relay 50 was of 10,000 ohms direct current resistance. It is understood, of course, that the values of these elements will be selected according to the delay required. This time delay permits relay 50 to close on a pulsation which is of dash length but not of dot length and the length is adjustable by selecting the proper resistor. When relay 50 does close, condenser 51 is effectively removed from the coil 50 by opening of contacts 200 and 201 allowing the relay to have instantaneous release action. This release is effected at the end of the pulsation because the return lead from relay 50 goes through contact 65 ordinarily to arm 66 which is connected to the negative source of power through contact 127 of reset relay 68. However, when relay 41 releases, contact 65 is removed from the negative

lead and relay 50 is no longer energized. At the end of the pulsation, when relay 41 is released, contacts 70 and 71 are closed, placing resistor 72 of approximately 500 ohms directly across condenser 51 rapidly dissipating its charge during interval and space time. The reason therefor is to permit the charging time of this condenser to be uniform with the beginning of each pulsation as otherwise it would accumulate a charge which would make the delay time of coil 50 variable. In the modified embodiment, advantage is taken of this variation but in the instant embodiment, the condenser is substantially discharged at the end of each pulsation.

When arm 25 is set on the dot circuit, negative potential originating at electrical line L1 is applied to stepper arm 37 at the beginning of a pulsation and is immediately placed on relay arm 75 through the dot wire 69. Since relay 50 is fed with each pulsation through contact 65, it starts timing the pulsation but is not allowed to close unless a dash is received. Therefore, if the incoming signal is a dot and conforms to the switch S1 setting, the reset is not operated and the stepper is advanced. However, if a dash is received and relay 50 allowed to close, relay arm 75 which has negative potential makes contact with relay arm 76 which in turn operates the stepper reset relay 68. As hereinafter explained, this causes the stepper switch to reset to starting position because the proper sequence of call characters has not been observed. During the first pulsation, there has been no checking for interval or space as the stepper arm 77 has not yet advanced to the first position. It will be observed that this second level of the stepper represented by switch S2, follows one step behind the dot and dash level as represented by switch S1.

Dot and dash acceptance and rejection

When selector arm 25 or any other selector arm of switch S1 is set to the dash circuit in accordance with the desired call, the negative potential is applied to and immediately operates relay 82 which is energized through contact 81 and armature 80 of relay 50 and locked in closing position by relay 85. In the drawing, those terminals marked —, are connected directly to lead line 88 which is normally connected to the negative source L1 through contacts 155 and 152 as hereinafter described. Until the alarm is operated, line 88 is always negative. The relay 85 immediately closes on each incoming pulsation following a letter space and remains closed until another letter space is received. As will hereinafter be described, relay 85, which is delayed in releasing, interprets, together with its associated relay 90, interval and space signal components and provides an electrical lock on relay 82 through contacts 83 and 84.

Simultaneously with the operation of relay 82, the negative potential placed on the dash circuit wire 89, is applied through armature 91 and contact 92 to contact 93. Relay 41 being thus far closed, no potential gets to reset relay 68. If the incoming pulsation is a dash so that sufficient time is given relay 50 to close, contacts 80 and 81 are opened, which opens the ground circuit of relay 82 releasing it notwithstanding the previous locking effect secured by armature 95 and contact 96 through the contacts 83 and 84. However, if a dot is received and contacts 80 and 81 are not opened, relay 82 remains locked in through contacts 95 and 96 and contacts 83 and 84. Since after the beginning of the pulsation,

negative potential was placed through contacts 91, 92 to contact 93, the reset 68 is operated at the end of a dot pulsation when the armature 97 returns to normal position. This shows that at the beginning of a pulsation when S1 is on the dash circuit, relay 82 is immediately closed and negative potential placed on contact 93 through contacts 91 and 92 so that if only a dot is received, the reset will be operated when armature 97 makes contact with 93 at the end of the dot pulsation. Since the negative potential supplied relay 82 is broken at the end of the dot pulsation, it is necessary to have an electrical lock on relay 82 through contacts 95 and 96 and through contacts 83 and 84 in order to maintain negative potential on 93. This negative potential will remain on 93 until a dash is received so that anything else than a dash will operate reset relay 68 and return the selector or stepper switch to starting position. When, however, a dash is received sufficient to close relay 50, contacts 80 and 81 are opened so that relay 82 releases removing the negative potential from contact 93. Hence, it can be seen that if the pulsation is of sufficient length to constitute a dash, subsequent opening of relay 41 will not operate the resetting relay 68. The stepper, however, is operated at the end of the pulsation as hereinabove stated. The acceptance or rejection of dot character pulsations follows the explanation hereinabove set forth. Thus, with each advance of the stepper, the next pulsation is checked to see whether it corresponds to the original setting of the selector switch arms.

Interval and space acceptance and rejection

Relay 41 supplies the potential of the incoming pulsations not only to the dot and dash relays but simultaneously to the interval and space relays contained in the interval and space interpreter circuits 98. Switches S1 and S2 respectively represent a series of switches which are mounted on a common support. Switch arms 77 and 37 are ganged for simultaneous movement so that as arm 37 advances, arm 77 similarly advances along the successive switch contacts 100-105 etc. Switch arm 77 is directly connected to the negative lead L1 so that it has negative potential on it at all times. It will be observed that the initial position of switch arm 77 is at contact 100 which is not connected to any circuit inasmuch as spaces and intervals are checked only after the first letter component, i. e. either a dot or dash, has been received so as to advance switch arm 77 to the switch contact 101. At this point, timing for spaces and intervals commences. Assuming now that switch contact 101 is on an interval circuit as illustrated in Fig. 1, negative potential is placed on contact 106 which is not engaged with armature 107 as relay 85, due to its delayed action is still closed for a period of time not exceeding interval time. If a space is made allowing relay 85 to release, armature 107 engages contact 106 completing the circuit to reset relay 68 bringing the selector relay to starting position by its spring return 44. Thus, it can be seen that if the selector switch S2 is placed at "interval" and a space sufficient to release relay 85 is received, the apparatus will reset and reject the call. If the interval was not of sufficient duration to cause contacts 106 and 107 to engage, then the next pulsation would maintain relay 85 energized through contact 86 so that reset potential would not get to the relay 68. When S2 is set to the space circuit, negative potential is immediately placed on armature 113

which is not engaged with contact 111 because of the delayed release time of relay 85. Negative potential is, however, placed on contact 112 and through armature 113 to contact 114. Contact 114 does not engage armature 97 until the beginning of the next pulsation. If a space is not received, however, when the switch arm is set for space, as set forth, then relay 85 is not given sufficient time to drop out before the beginning of the next pulsation. It will be recalled that relay 90 is associated with relay 85, such relay 90 is energized only when relay 85 is released. Therefore, contacts 112 and 113 are engaged and negative potential from the space circuit is on contact 114 so that at the beginning of the next pulsation, armature 97 applies the potential to reset relay 68.

If, however, a space is made allowing relay 85 to drop out, engaging contacts 110 and 111, relay 90 is operated removing the negative potential from contact 116 by opening the circuit at 112 and 113. Thus, when a space is made when the switch is set for a space, there will be no rejection and the stepper arms will advance another step. It will be noted that when relay 90 closes, it will electrically lock itself through contacts 115 and 116 through arm 117 and contact 118 of relay 41. At the beginning of the next pulsation it is evident that engagement between contacts 119 and 111 would be broken by the operation of relay 85. This would release relay 90 which would operate the reset through the contacts 112 and 113 through the armature 117 and contact 114. It is necessary, however, that this is not effected and, accordingly, relay 90 is locked so as to remain energized through its contact 115 and armature 116 which receives negative potential from the armature 117 and contact 118. At the end of the pulsation, when armature 117 returns to normal position, the lock is broken, arm 77 advances to the next circuit position and timing procedure repeats for the next position.

It will be noted that the provision of switches S1 and S2 as described, makes specific wiring for a predetermined call unnecessary because the individual switch arms can be set as required for practically any condition. In the bank of switches of selector S2, each switch bank of four terminals has a neutral terminal which precedes the other switch positions. When a bank switch arm is on the neutral position, any time between pulsations will be accepted whether it is an interval or a space. It will be appreciated that the flexibility of the apparatus is considerably enhanced thereby. Two advantages of the neutral position are the following:

1. In S O S signals, the letters are very often run together without regard to intervening spaces. Automatic transmitters of S O S signals usually run the letters thus together. If the apparatus were set to receive a space between the letters, a rejection would be effected and the apparatus would not respond. However, by using the neutral position between letters and intervals between the letter components, the S O S will come through whether or not the letters are duly separated. It will further be observed that in the event a space is received during part of a letter, it will be rejected because the switch is at the interval setting.

2. Experienced radio operators of Morse code transmission often run letters together which cannot possibly form a false letter. Thus, A and N are never run together because they would form a P. However, letters C Q are very often run to-

gether without proper space because they cannot be mistaken for another letter. Thus, a greater variance of sending speed may be accommodated by the apparatus by setting the selector arm at a neutral position between letters such as C and Q, so that the letters will be individually accepted whether they are run together or whether the proper spacing is observed. This feature provides highly desirable flexibility of code speed reception and the adaptability of the apparatus to varying conditions is considerably increased.

Reset operation.

As the reception of the switch arms progresses, switch arms 37 and 77 advance so as to wipe over the selector switch contacts. As hereinabove stated, if any improper letter component is received, the spring 44 returns the toothed wheel and its switch arms to the home or initial position. The operation of the reset relay 68, which through its mechanical action accomplishes this, also carries electrical contact armatures 125 and 126 and contacts 127 and 128. Upon operation of the reset relay, armature 125 is disconnected from contact 127 which removes the negative potential from armature 40 and 66, thereby stopping all further operation of stepper relay 45 and timing relay 50. This results because negative potential which is on armature 40 from contact 127 ordinarily supplies closing potential for relay 50 as well as relay 45. However, after a release or reset has been effected, it is necessary to disable the apparatus until a space is received. Otherwise, the apparatus might reject part of a letter and then proceed on the next part as if that next part were a complete letter in itself. By requiring a space to be observed after each rejection, whole letter operation is assured. The disabling of the apparatus until a space is received is accomplished by means of the electrical lock on relay 68 through contacts 130, 131 of relay 85 which is itself slow to release and will not drop out until a letter space is made. Thus, when a rejection is made, all circuits save the relay 85 are disabled and the release of relay 85 starts the action again. This is accomplished by relay 68, contact 128 and armature 126, which provides an electrical lock on the reset relay 68 through armature 130 and contact 131 of relay 85. It will be remembered that relay 85 is maintained energized by means of the incoming pulsation through contact 86 and arm 87. When a sufficient letter space is made allowing relay 85 to release, armature 130 leaves contact 131, opening the electrical lock on relay 68 which also restores armature 125 to contact with 127 which restores negative potential to armature 40. Thus, the next letter is ready to be checked since all circuits are in operation.

Alarm

When the proper signal for which the apparatus is set up is received, the alarm bell 150 is sounded so as to provide an audible indication of the reception of a call. This is accomplished in the following manner:

Originally, when setting up the call on the selector switches, the last switch representing a letter space is set at the alarm contact instead of a space. This means that after the switch arms have progressed through the call, switch arm 77 with its negative potential will be effectively applied to the alarm circuit, as represented by the switch contact 104 of the switch S2 according to the set-up in Fig. 1. Negative potential is applied

to relay 151 through contacts 160 and 161 when relay 85 falls out with the last letter space so as to attract the armatures 152 and 153 of relay 151. Negative potential from lead L1 is thereby applied through armature 153 to contact 154 so as to operate the bell 150. Simultaneously, attraction of armature 152 disconnects the negative potential from contact 155 which cuts off any further current to the apparatus. This stops all operation of the apparatus except for the relay 151 which is connected to the negative lead L1 through selector switch arm 77 connected thereto. This connection is not shown on the drawing for purposes of clarity. The bell 150 will then continue to ring until manually operated reset switch 156 is closed. Manual operation of this switch applies the negative potential to reset relay 68 which thereupon closes and resets the stepper the same as resets are made by rejections. This returns arm 77 to switch contact 100 so as to remove the negative potential from the alarm circuit whereupon relay 151 is released and the bell stops ringing.

It will be understood that the last letter must not be followed by a dot or dash as otherwise it would constitute a different letter for which the apparatus was not set. Therefore means are provided to reset the switches if a letter space is not made when arm 77 engages the alarm circuit and another dot or dash is added to the last character instead of a space. This is accomplished by setting the selector switch following the last dot or dash setting to the reset circuit which goes directly to relay 68. Thus, if another dot or dash is applied through the switch arm 37 it will energize relay 68 so as to reset the stepper switches. In this event, no alarm will be sounded.

It will be recalled that resistors 52-54 are selected in order that the closing time of relay 50 may be predetermined depending upon whether faster or slower speeds are to be accommodated. In the same manner, the interval interpreter circuit as represented by relay 85 is provided with timing condensers 175, 176 and 177 in order that the delay time of relay 85 may be adjusted. This is for the purpose of presetting the apparatus in accordance with the expected speed of reception. It is, of course, understood that the apparatus will operate satisfactorily over a considerable deviation from a predetermined setting. This is made possible by the delayed closing and releasing relays which start timing all pulsations as dots until they extend to dash length. In other words, a dot may be any length, however short, until it extends to dash length whereupon it is, of course, considered a dash, and a dash may be of any length as long as it exceeds the dash time which is set by the resistors 52-54. Similarly, the interval time may be as long as desired until it becomes space time. This provides extremely wide variation in code speed reception since dashes are normally three times as long as intervals. The time delay relays are set to operate at a timing point one-third the normal dash length and one-third of the letter space time so that a signal component which does not effect operation of the two timing relays is a dot or an interval respectively.

In a modified embodiment, I have devised means to render the apparatus substantially automatically responsive to the desired signal irrespective of any settings of relays in anticipation of code speed conditions. This is accomplished by selecting a value of resistor 72 which will delay the leakage time of the condenser 51. Ordinarily, resistor 72 may be of a value of 500 ohms, while

condenser 51 is 10 mfd. However, by increasing resistor 72 to a much higher value, i. e. approximately 5000 ohms, the discharging of the condenser 51 is determined by the operating speed of the pulsing relay 41 which effects continuous making and breaking of the contacts 70 and 71. If the operation is very fast, the condenser charge will not have an opportunity to leak off between pulsations and a partial charge will always remain thereon decreasing the delay time and increasing the closing speed of the relay 50 to conform with the speed of the incoming signals. This action will render the dot and dash interpreter circuits automatically adaptable to varying speeds. It is also necessary to similarly control the space and interval time. Referring to Fig. 2, the required modification of the delayed release relay 85 is illustrated. The feature of adaptability is accomplished by inserting resistor 185 in series with condenser 186 across the relay winding so that the condenser is not immediately fully charged. In addition, contacts 187 and 188 are provided to short out resistor 185 when pulsing relay 41 is released which allows condenser 186 to hold relay 85 closed for the duration of time in proportion to the charge received through resistor 185 while relay 41 is closed. If the operation of relay 41 is fast, condenser 186 is correspondingly charged to a lesser degree which allows relay 85 to drop out more rapidly at signal interruptions, the term "interruptions" referring to either intervals or spaces.

While there has been described what at present is considered a preferred embodiment of the invention, it will be evident that many changes and modifications may be made therein without departing from its spirit. It is therefore aimed in the appended claims to cover all such changes and modifications which fall within the true spirit and scope of the invention.

I claim:

1. In a signalling system for identifying a transmission of Morse code letter pulsations constituting a desired call, the combination of an alarm, electrical circuit means to operate said alarm, a selector device operating to progress in steps from a starting position to a position where it closes said electrical circuit means when a complete predetermined transmission has been received, release relay means for returning said selector device to said starting position when an undesired call is received, said selector device comprising a first series of switch elements for preselecting the desired dot and dash characters, a second series of switch elements for pre-selecting the space and interval interruptions and switch arm means for progressing along the respective series of switch elements as the proper pulsations from said transmission are applied to said system, a slow closing relay energized by said pulsations and operative to close when a pulsation of dash length is received, said release relay means being operated by said slow closing relay through said first series of switch elements according to the preselection of said dot and dash characters thereon, a slow releasing relay energized at each received pulsation and operative to open at a signal interruption of space length, said release relay means being operated by said slow releasing relay through said second series of switch elements according to the preselection of said space and interval interruptions thereon, non-operation of said slow closing and slow releasing relays respectively determining the dot and interval natures of a received pulsation, and said second series of switch elements

including a neutral position by which its switch elements remain unconnected to either space or interval positions so as to prevent operation of said release relay means through said second series of switch elements.

2. In a signalling system for identifying a transmission of Morse code letter pulsations constituting a desired call, the combination of an alarm, electrical circuit means to operate said alarm, a selector device operating to progress in steps from a starting position to a position where it closes said electrical circuit means when a complete predetermined transmission has been received, release relay means for returning said selector device to said starting position when an undesired call is received, said selector device comprising a first series of switch elements for pre-selecting the desired dot and dash characters, a second series of switch elements for pre-selecting the space and interval interruptions and switch arm means for progressing along the respective series of switch elements as the proper pulsations from said transmission are applied to said system, a slow closing relay energized by said pulsations and operative to close when a pulsation of dash length is received, said release relay means being operated by said slow closing relay through said first series of switch elements according to the preselection of said dot and dash characters thereon, a slow releasing relay energized at each received pulsation and operative to open at a signal interruption of space length, said release relay means being operated by said slow releasing relay through said second series of switch elements according to the preselection of said space and interval interruptions thereon, non-operation of said slow closing and slow releasing relays respectively determining the dot and interval natures of a received pulsation, said selector device including an actuating relay, said actuating relay being directly fed by said pulsations, a pair of contacts on said actuating relay, said pair of contacts being electrically interposed between said first series of switch elements and said slow closing relay and being normally closed, said pair of contacts energizing said release relay when a dot is received when said first series of switch elements is set for dash operation.
3. Apparatus according to claim 2 and including a second pair of contacts on said actuating relay, said second pair of contacts being interposed between said first series of switch elements and said slow releasing relay and being normally open, said second pair of contacts energizing said release relay when an interval occurs when said first series of switch elements is set for space operation.
4. In a signalling system for identifying a transmission of Morse code letter pulsations constituting a desired call, the combination of an alarm, electrical circuit means to operate said alarm, a selector device operating to progress in steps from a starting position to a position where it closes said electrical circuit means when a complete predetermined transmission has been received, release relay means for returning said selector device to said starting position when an undesired call is received, said selector device comprising a first series of switch elements for pre-selecting the desired dot and dash characters, a second series of switch elements for pre-selecting the space and interval interruptions and switch arm means for progressing along the respective series of switch elements as the proper pulsations from said transmission are applied to said system, a slow closing relay energized by said pulsations and operative to close when a pulsation of dash length is received, said release relay means being operated by said slow closing relay through said first series of switch elements according to the preselection of said dot and dash characters thereon, a slow releasing relay energized at each received pulsation and operative to open at a signal interruption of space length, said release relay means being operated by said slow releasing relay through said second series of switch elements according to the preselection of said space and interval interruptions thereon, non-operation of said slow closing and slow releasing relays respectively determining the dot and interval natures of a received pulsation, and said second series of switch elements

11

slow closing relay energized by said pulsations and operative to close when a pulsation of dash length is received, said release relay means being operated by said slow closing relay through said first series of switch elements according to the pre-selection of said dot and dash characters thereon, a slow releasing relay energized at each received pulsation and operative to open at a signal interruption of space length, said release relay means being operated by said slow releasing relay through said second series of switch elements according to the preselection of said space and interval interruptions thereon, non-operation of said slow closing and slow releasing relays respectively determining the dot and interval natures of a received pulsation, a condenser and resistor in the circuit of said slow closing relay for regulating its closing time, said slow closing relay including a normally closed pair of contacts connecting said condenser to the winding of said slow closing relay, operation of said slow closing relay opening said contacts so as to remove the condenser from the relay circuit and permit instantaneous release thereof.

5. In a signalling system for identifying a transmission of Morse code letter pulsations constituting a desired call, the combination of an alarm, electrical circuit means to operate said alarm, a selector device operating to progress in steps from a starting position to a position where it closes said electrical circuit means when a complete predetermined transmission has been received, release relay means for returning said selector device to said starting position when an undesired call is received, said selector device comprising a first series of switch elements for preselecting the desired dot and dash characters, a second series of switch elements for preselecting the space and interval interruptions and switch arm means for progressing along the respective series of switch elements as the proper pulsations from said transmission are applied to said system,

a slow closing relay energized by said pulsations and operative to close when a pulsation of dash length is received, said release relay means being operated by said slow closing relay through said first series of switch elements according to the preselection of said dot and dash characters thereon, a slow releasing relay energized at each received pulsation and operative to open at a signal interruption of space length, said release relay means being operated by said slow releasing relay through said second series of switch elements according to the preselection of said space and interval interruptions thereon, non-operation of said slow closing and slow releasing relays respectively determining the dot and interval natures of a received pulsation, condensers in the circuits of said slow closing and slow releasing relays for determining the time constants of said slow closing and slow releasing relays and means to feed said condensers by incoming pulsations so as to adjust the time constants of said slow closing and slow releasing relays according to the speed of incoming pulsations.

WILLIAM WALTER McGOFFIN.
